GRINDING DEVICE

John Emerson, Irvington, N. J.

Application September 22, 1938, Serial No. 231,114

3 Claims. (Cl. 51—73)

The present invention relates to a grinding device and it particularly relates to a grinding device for crankshafts.

Although the present invention will be particularly described in its application to the grinding or crankshafts for automotive and similar internal combustion inventions, it is to be understood that it has a broader application and may be applied to many other uses.

10 Most crankshafts of automobiles after substantial wear tend to lose their desired cylindrical bearing surface and tend to become oval or flat or off-center on one or more portions of the periphery thereof.

15 It is usually necessary to dismantle the entire engine at substantial cost in order to grind the journals and center them.

When the crankshafts have been removed from the car, it is necessary to set them up upon 20 a relatively complicated machine which will enable proper centering and grinding operations of the bearing portions of said crankshaft.

It is among the objects of the present invention to prepare an improved journal grinding 25 device which may accurately center and grind and restore a true peripheral surface to journals of automobile and other crankshafts without heavy labor costs and without the necessity of dismantling and/or mounting the entire engine 30 of the automobile.

Another object is to provide an improved grinding device which will be readily applicable to crankshafts without necessitating placement of said crankshafts in a special grinding apparatus with accurate centering and positioning thereof.

Other objects will be obvious or will appear during the course of the following specification.

In accomplishing the objects of the present invention, it has been found most satisfactory to 40 provide a grinding device which is readily assembled and dismantled and which may be assembled in such a way as to enclose or grasp the journal of the crankshaft without the necessity of dismantling the engine structure and dismounting the same.

In one form of the invention, a grind ring is provided carrying suitable emery cloth or other abrasive material which grind ring is split and 50 may be positioned so as to grasp the journal to be ground.

The split portions of the grind ring may have a resilient connection to each other and may 55 be so constructed as to enable adjustment of

the tension and adjustment of the grinding diameter.

The grind wheel is preferably held inside of a drive wheel to which it has a loose connection and within which it floats, the driving wheel 5 being preferably also split and having suitable connections, to a source of energy as for example, a belt receiver or grooved periphery.

The rotatable sub-assembly of the grind ring and the driving ring may be mounted in a suitable bracket serving as a bearing for the sub-assembly and which may be placed upon the sub-assembly after the sub-assembly has been positioned upon the surface to be ground.

At the same time, other journals or portions 15 of the crankshaft may be suitably supported so as to enable the sub-assembly, above described, to be rotated upon the journal to be rounded or given its proper contour.

The above and other objects will appear more 20 clearly from the following detailed description when taken in connection with the accompanying drawings, will illustrate a preferred embodiment of the inventive idea.

Referring to the drawings:

Figure 1 is a perspective view of the grinding device of the present invention with parts broken away to more clearly show the construction thereof;

Figure 2 is a transverse sectional view upon 30 the line 2—2 of Figure 1 upon enlarged scale, as compared to Figure 1;

Figure 3 is a transverse sectional view upon the line 3—3 of Figure 2 showing the rotating grinding sub-assembly and the manner in which it is supported;

Figure 4 is a detailed sectional view of the connection between the split portions of the grinding ring upon enlarged scale as compared to Figure 3, more clearly to show the construction;

Figure 5 is a diagrammatic perspective view illustrating how the crankshaft may be mounted to enable grinding of the journals thereof by the grinding device of the present application.

Referring to Figures 1 to 5, the crankshaft A is provided with a plurality of journals or bearings B, C, D, E and with the shaft F.

The journal B is the particular journal to be ground in the manner shown in Figure 5.

The grinding device, as best shown in Figure 1, consists of a grind ring G, a drive ring H, a bearing mount I and support mounts J and K.

The motor L may be located in any desired position to drive the construction.

Referring specifically to Figures 1 to 3, the grind ring G consists of two elements 10 and 11 which are connected by the bolts 12 and 13. The ends of the sections 10 and 11 are in contact at 14 at the bolt 12, but are separated at the ends 15 and 16 at the bolt 13 with the springs 17 pressing said ends 15 and 16 apart.

The bolts 12 and 13 have heads 17, 18, which are accessible through the openings 19 and 20 in the lower ring section 11.

The construction of the bolt 13 is more fully shown in Figure 4 and it will be noted that the ends of the spring 17 fit in the recesses 21 and 22 of the faces 15, 16 of the grind ring G.

The grind ring G is also provided with recesses 23 and 24 which have the clamp plates 25, 26 holding the abrasive strips 27 and 28 in position. The ends 29 and 30 of the strips 27 and 28 are free since the grind ring G will be turned in the direction indicated by the arrow 31.

The journal B is adapted to fit within the opening of the grind ring G which may be placed thereon by opening or loosening the bolts 12 and 13 and then tightening them up after the two halves 10 and 11 have been placed in position on the journal B.

The grind ring G is driven by the drive ring H by the projecting elements or fins 32, 33 and 34 which fit into the recesses 35, 36 and 37 in the interior of the drive ring H.

The drive ring H is made up of two half sections 39 and 40 which have the shoulders 41 and 42 (see particularly Figure 2) and the lips 43 and 44 between which is the groove 45 to receive the belt 46 (see Figures 2 and 5) driven by the motor L.

The two segments 39 and 40 are held together by the pins 46 and 47 (see Figure 3) which pins are in turn held in position by the transverse pins 48, 49, 50 and 51. These pins 48 and 47 fit in recesses in contacting faces 52 and 53 of the drive ring segments 39 and 40.

The upper segment 39 as shown in Figure 3 is provided with an opening 54 into which projects the pin 55 from the segment 10 of the grind ring G.

Through the sides of the opening 54 extend the transverse pins 56 and 57 against which the upper end of the pin 55 contacts.

The connection of the pin to the opening 54 and the projections or fins 32, 33 and 34 in the slots or recesses 35, 36 and 37 provides a free floating drive connection between the grind ring G and the drive ring H.

The support structure I consists of two plates 58 and 59 having circular openings or recesses therein which are adapted to be placed on and engage the shoulders 41, 42 of the outer ring or drive ring H, as shown in Figure 2.

The front end of the recess 60 is open so as to enable more ready assembly of the plates 58 and 59 with the ring sub-assembly G and H after said sub-assembly has been placed upon the journal B.

The plates 58 and 59 are held together by the bolts 61, 62, 63 and 64 each of which is provided with a spacer sleeve 65 having the shouldered end portions 66 fitting in openings in the plates 58 and 59.

Each bolt is provided with a hexagonal head 67 with a washer 68 and a wing nut 69 for tightening the same.

It will be noted from Figure 1 that the wing nuts are all positioned on one side except for the bolt 63.

The plates 58 and 59 carry the blocks 70, 71 having the openings 72, 73 and 74 extending entirely through the blocks 70 and 71 but terminating at the plates 58 and 49.

These blocks 70 and 71 are held in position by the bolts 75 and 76.

The blocks are also provided with set screws or bolts 77, 78 and 79 which are designed to clamp in position the structure rods 80 and 81 which hold the grinding structure in position in respect to the supports J and K.

The supports J and K are in turn provided with the blocks 82 and 83 which receive the other ends of the rods 80 and 81.

The blocks 82 and 83 also receive the uprights 84 and 85.

The uprights are held in position by the set screws 86 and 87. The upper ends of the uprights 84 and 85 support the lower ends 90 and 91 of the straps 88 and 89, by the screws 92 and 93.

The straps 88 and 89 have outwardly bent portions 94 and 95 to ends of which are held the straight strap portions 96 and 97 by means of the bolts 98 and 99 having the lock nuts 100 and 101.

As indicated in Figure 5, the recesses 102 and 103 formed between the bends 94 and 95 and the straight strap elements 96 and 97 are designed to receive the journals C and D on the crankshaft structure.

In operation, the segments 10 and 11 of the grind ring G, 49 and 40 of the drive ring H and the plates 58 and 59 are all separated by loosening the bolts 17 and 18, the pins 46 and 47 and the bolts 61 and 64 all inclusive, prior to placement upon the journal B.

The grinding combination G, H and I has in the meanwhile been dismounted from the rods 80 and 81 by loosening the set screws 77 and 79.

The crankshaft, as shown in Figure 5, may have one end 104 clamped in the vise 105 by the handle 106 and its other end 107 may carry the usual gear 108. The grind ring G is first placed upon the journal B with the emery cloth 27 and 28 in position therein and the bolts 12 and 13 are tightened up.

The bolts 17 are tightened so that the two faces 14 contact while the bolt 13 is merely tightened until there is sufficient tension on the spring 17 to assure that the emery cloth 27 and 28 will grind the face of the journal upon a true center.

Then, the two segments 39 and 40 of the drive ring H may be attached with pins 46 and 47 being in proper position and with the pin 55 being received in the recess 54.

The belt 46 may then be attached.

The plates 58 and 59 may then be placed with the edges of the recesses 60 upon the shoulders 41 and 42.

The bolts 61 and 64 may then be applied to connect the plates 58 and 59, then the straight straps 96 and 97 may be loosened by opening the nuts 100 and 101 and the journals B and C may be positioned in the spaces 103 and 102.

The straight straps 96 and 97 may be connected by the nuts 100 and 101 to cover the openings 102 and 103 and the bars 80 and 81 are then fixed in position in one of the blocks 70 and 71 by the set screws 77 and 79.

Then the motor L may be started driving the grind ring H and the drive ring G until the grinding has been completed.

Among the important features of the present invention as shown in Figures 1 to 5 are the float-

ing drive resulting from the pin 55 fitting in the opening 54 and the adjustable resilient connection indicated in Figure 4 which is accessible through the opening 150 in the drive ring H.

5 By the device as shown, it is possible to grind the journals of an automotive crankshaft without removing the crankshaft from the car and it is possible to grind these journals absolutely round without an elaborate centering machine.

10 Due to the free floating connection 54, 55 there is no direct bearing pressure, which might tend to give an unbalanced grinding.

Moreover, adjustment of the bolts 13 indicated in Figure 4, enables the device to be readily adjusted to meet various conditions.

15 The journal will be ground accurately in line and on center by reason of the device as shown and a great amount of time and labor will be saved because dismounting of the automotive engine or motor is not required.

20 It is apparent that the specific illustrations shown above have been given by way of illustration and not by way of limitation and that the structures above described are subject to wide variation and modification without departing from the scope or intent of the invention, all of which variations and modifications are to be included within the scope of the present invention.

25 What is claimed is:

30 1. A grinding device comprising a rotatable grind ring to receive interiorly thereof a journal to be ground, a rotatable drive ring encircling and carrying said grind ring, a support for carrying said drive ring and means for causing rotation of said drive ring around said journal to grind the same, said rings being split so that they may be placed upon the journal, the split elements of said grind ring being separated by a coll

spring and a bolt adjustably to draw up said coll spring.

2. A grinding device for centering and facing the journals of an automobile crankshaft comprising a split ring carrying an abrasive material 5 on the interior face thereof to be placed on and rotated around one of the journals of said shaft, adjustable means to regulate the size of the opening in said ring, a second split ring encircling said first split ring, free floating connections between 10 said split rings to cause said rings to rotate together, driving means on said second ring, bearing means on said second ring, a bearing support to receive said bearing means, a second support for the other journals of the crankshaft while 15 said one journal is being ground and connecting means to connect the supports together, said floating connections including projections from the outside periphery of the first ring and recesses on the inside periphery of the second ring 20 receiving said projections.

3. A grinding device comprising a rotatable grind ring to receive interiorly thereof a journal to be ground, a rotatable drive ring encircling and carrying said grind ring, a support for carrying 25 said drive ring and means for causing rotation of said drive ring around said journal to grind the same, said rings being split so that they may be placed upon the journal, said drive ring having a radial opening at one side thereof and 30 said grind ring having an unthreaded pin projecting thereinto, said opening having parallel rod like contact members positioned transversely to the direction of rotation and parallel to the axis of rotation, said unthreaded pin being positioned between and contacting with said rod members.

JOHN EMERSON.
